Primary Examiner — Darlington Ly(74) Attorney, Agent, or Firm — D’Ambrosio & Menon, PLLC; Usha Menon(57) CLAIM

The ornamental design for a utility terrain vehicle as shown and described.

DESCRIPTION

FIG. 1 is a front perspective view of the utility terrain vehicle showing my new design;

FIG. 2 is a rear perspective view thereof;

FIG. 3 is a left side elevational view thereof;

FIG. 4 is a right side elevational view thereof;

FIG. 5 is a front elevational view thereof;

FIG. 6 is a rear elevational view thereof;

FIG. 7 is a bottom plan view thereof; and,

FIG. 8 is a top plan view thereof.

The broken lines shown in the figures are for the purpose of illustrating portions of the utility terrain vehicle, which form no part of the claimed design.

1 Claim, 8 Drawing Sheets(56)
